V. H. FAIRLESS,
HOSE PROTECTOR,
APPLICATION FILED MAY 4, 1921.

1,423,409.

Patented July 18, 1922.

UNITED STATES PATENT OFFICE.

VICTOR H. FAIRLESS, OF TRENTON, TENNESSEE.

HOSE PROTECTOR.

1,423,409.

Specification of Letters Patent. Patented July 18, 1922.

Application filed May 4, 1921. Serial No. 466,737.

To all whom it may concern:

Be it known that VICTOR H. FAIRLESS, a citizen of the United States, residing at Trenton, in the county of Gibson and State 5 of Tennessee, has invented certain new and useful Improvements in Hose Protectors, of which the following is a specification.

The present invention relates to improvements in hose protectors, and it more particularly relates to a device adapted to encircle the ankle of the wearer to form a guard to protect the hose from the liquid polish or other material used to clean and shine shoes. It often happens that boot-blacks are careless in the application of this liquid to the shoe, which is a preliminary operation to applying the paste polish, and as a result the socks or hose are splashed and stained by the liquid material. Particularly is this so with white hose which are discolored and ruined by random splashes of the polish or other liquid, and which of course become unsightly before they can be removed and changed. Furthermore, light 25 colored hose are frequently soiled just along edge of low shoes by the polishing brush or cloth being rubbed across them.

It is an object of the present invention to provide an adjustable guard to fit about the 30 ankle and protect the hose, and which will be of an inexpensive construction and one which will adapt itself to low quarters particularly and also to high shoes.

With the foregoing and other objects in 35 view, the invention will be more fully described hereinafter, and will be more particularly pointed out in the claim appended hereto.

In the drawings, wherein like symbols refer to like or corresponding parts throughout the several views,

Fig. 1 shows in dotted perspective the outline of a low shoe or oxford provided with an improved protector constructed according to the present invention with the trousers indicated above the same;

Fig. 2 is a similar view taken from an opposite angle and showing the connecting device for the protector band;

Fig. 3 is also a dotted perspective view of a high shoe showing the application of the improved device in inverted position;

Fig. 4 is a plan view of the protecting device; and

Fig. 5 is an edge view thereof.

Referring more particularly to the draw-

ings, the improved protector consists of a band 1 of thin, light material preferably celluloid having a suitable depth to cover entirely the area of the hose apt to be splashed by a liquid, blackening, cleaning, or other material used in bootblack establishments. One edge 2 of the band 1 is cut off straight, while the opposite longitudinal edge is provided with a wave-like form 65 which includes a pair of lugs 3 and 4 adapted to fit well inside the depressed portions 5 of the upper edge of the oxford for instance, as shown in Figs. 1 and 2. The lower edge of the band 1 is further formed with a 70 tab 6 near one end of the band for fitting beneath the tongue of the oxford, the position of which is also adequately illustrated in Figs. 1 and 2.

A series of apertures or openings 7 are 75 made in one end of the band 1 to receive a hook 8 formed from one end of a single strand of wire 9 which has its intermediate portion looped outwardly to provide parallel legs 10 and 11 forming a finger piece 80 for the removal and insertion of the hook 8 into a selected opening 7. The other end of the strand 9 is engaged permanently with an end of a flexible tape 12 secured in any suitable manner to that end of the celluloid band 1 opposite the apertures 7.

In use, the band 1 is made to encircle the ankle of the wearer in the fashion, for instance, indicated in Figs. 1 and 2 where low shoes are worn. In this instance the 90 wave-like lower longitudinal edge of the band 1 is disposed downwardly with the lugs 3 and 4 fitting inside the depressed parts 5 of the shoe uppers, and the tab 6 resting beneath the tongue of the shoe so as 95 to center and assist in holding the protector in a proper relative position with respect to the shoe, and to the hose which it is desired to protect.

With the formation thus given the band 100 100 the hose will be entirely concealed and will be effectively guarded against any splashes of the blacking or other material. The hook 8 is engaged with a proper aperture 7 in order that the band 1 may be tightly fitted 105 in place. The number of the apertures 7 yield a wide range of adjustment to properly fit the ankle of any user, and, also, that the protector may be more or less overlapped at its free ends.

Now in case of high shoes, the band 1 is inverted as shown in Fig. 3, as the straight

edge 2 conforms better to the formation given the top of a high shoe. The band is disconnected in place and removed in the same manner as heretofore, and a full and adequate protection for the socks or hose is thus provided by a simple device which may be manufactured at a trifling cost.

It is obvious that various changes and modifications may be made in the details of construction and design of the above specifically described embodiment of this invention without departing from the spirit thereof, such changes and modifications being restricted only by the scope of the following claim.

What is claimed is:—

A hose protector, comprising a flat flexible band adapted to be placed about the ankle above a shoe top and adapted to over-

lap at its ends for fitting ankles of different thicknesses, said band having spaced depending lugs adapted to lie at the sides of the ankle and project into the shoe top and having a depending tab near one end for engagement beneath the tongue of the shoe, a flat tape carried on one end of the band and adapted to lie flat across the overlapping ends of the band to hold the same together, and a hook on the free end of the tape, said band having a longitudinal row of openings near its other end for selectively receiving the hook therein, whereby the hook may be adjustably secured to said other end of the band for closing the same in different sizes and at all times providing a substantially flat outer surface for the band, substantially as described.

VICTOR H. FAIRLESS.
